CLAIM

The ornamental design for footwear, as shown and described.

DESCRIPTION

FIG. 1 is a left side view of footwear showing our new design;

FIG. 2 is a right side view thereof;

FIG. 3 is a rear view thereof; and,

FIG. 4 is a rear perspective view thereof.

Broken lines illustrate features of footwear that form no part of the claimed design. Front, top, and bottom views are omitted because such views would not illustrate any features of the claimed design.
